(57) **CLAIM**

The ornamental design for a truck headlight, as shown and described.

DESCRIPTION

FIG. 1 is an exploded perspective view of a truck headlight; FIG. 2 is a perspective view thereof, with the lens removed; FIG. 3 is a perspective view thereof; FIG. 4 is a front view thereof, with the lens removed; FIG. 5 is a front view thereof; FIG. 6 is a front view thereof, of the lens; FIG. 7 is a rear view thereof; FIG. 8 is a left view thereof; FIG. 9 is a right view thereof; FIG. 10 is a top view thereof; and, FIG. 11 is a bottom view thereof.

The dashed or broken lines shown in the drawings depict portions of the truck headlight in which the design is embodied that form no part of the claimed design.
